CLAIM

The ornamental design for a cervical rest, as shown and described.

DESCRIPTION

FIG. 1 is a top plan view of the cervical rest of the present invention;

FIG. 2 is a bottom plan view thereof;

FIG. 3 is an elevation view of the end thereof closest to the top of the head of a user;

FIG. 4 is an elevation view of the end thereof closest to the shoulders of a user; and,

FIG. 5 is an elevation view thereof of the side closest to the right shoulder of a user, the elevation view thereof closest to the left shoulder of a user being a mirror image thereof.
